Application filed July 1, 1929. Serial No. 31,921. Term of patent 14 years.

To all whom it may concern:

Be it known that I, BENJAMIN S. NASH, a citizen of the United States, residing at Short Hills, in the county of Essex and State of New Jersey, have invented a new, original, and ornamental Design for a Textile Fabric or Similar Article, of which the following is a specification, reference being had to the accompanying drawing, forming part thereof.

In the drawing:—

The figure on the drawing is a plan view of a piece of textile fabric bearing my new design which is intended to be carried for-

ward or repeated ad libitum, as shown. The shading is on the drawing only to indicate more or less contrasting colors and not to indicate specific colors.

A single unit of my design is substantially comprised within the area defined by the indicating arrows shown on the drawing, which arrows form no part of the design.

I claim:

The ornamental design for a textile fabric or similar article substantially as shown and described.
